PHOTOGRAPHIC VIGNETTE.

No. 18,475.

Patented July 24, 1888.

UNITED STATES PATENT OFFICE.

JAMES C. ATKINS, OF MILTON, IOWA.

DESIGN FOR A PHOTOGRAPHIC VIGNETTE.

SPECIFICATION forming part of Design No. 18,475, dated July 24, 1888.

Application filed May 2, 1888. Serial No. 272,604. Term of patent 7 years.

To all whom it may concern:

Be it known that I, JAMES C. ATKINS, of Milton, in the county of Van Buren and State of Iowa, have invented or produced a new and original Design for a Photographic Vignette Mounting; and I do hereby declare that the photographic illustration accompanying this specification gives to any one skilled in the art to which this invention pertains a defined and thorough description of my invention, that is sufficient to enable any one skilled in such art to use my invention.

To particularize: The design consists in a special configuration and ornamentation of a photographic vignette mounting for a secret society known as the "Order of Knights of Pythias," the same comprising a border having an inner marginal configuration and ornamentation in the form of a band representing the exterior marginal figure of a shield, and said border being ornamented, exterior of said shield-like figure, with various emblems peculiar to said secret order, comprising figures above the shield-like figure representing a helmet and battle-axes, a serpent-like rod, and a spur, and below these, on the one side, fig-

ures representing cross-sabers, a death-head, a triangle, and a sprig of acacia, and on the other side of the inner margin of the border or shield-like figure figures representing cross-sabers, sandals, an open book, and a cross, while below the shield-like inner marginal figure is a scroll having on it "K of P," all of said emblems being exterior to the shield-like figure.
